United States Patent Office.

JOHN JOHNSON, OF BARRINGTON, NEW YORK.

Letters Patent No. 73,901, dated January 28, 1868.

IMPROVED DEVICE FOR SHARPENING HORSE-SHOE CALKS.

The Schedule referred to in these Letters Patent and making part of the same.

TO ALL WHOM IT MAY CONCERN:

Be it known that I, JOHN JOHNSON, of Barrington, county of Yates, and State of New York, have invented a new and useful Improvement in Machine for Sharpening Horse-Shoe Calks; and I do hereby declare the following to be a full, clear, and exact description of the same, reference being had to the accompanying drawings, in which—

Figure 1 is a perspective view of my improved machine or sharpener, represented as applied to the shoe upon the horse's foot, and adapted to operate upon the toe-calk.

Figure 2 is a vertical section of the same, taken in the direction of the length of the clamp-bar.

Figure 3 is a perspective view of the circular file detached.

Similar letters of reference denote corresponding parts in all the figures.

My invention relates to a novel construction and arrangement of parts of a machine for sharpening horse-shoe calks, adapted to be used for sharpening the calks while the shoe is secured to the horse's foot, thereby obviating the necessity for removing the shoe for that purpose; and it consists in the employment of an adjustable clamp, adapted to be secured to the shoe, and armed with a rotary, circular, or cylindrical file, operating as hereinafter described. It further consists in making the rotary file adjustable relative to its holding-clamp and the shoe in such manner as to adapt it to operate upon the several calks without changing the position of the clamp, as hereinafter described.

In the accompanying drawings, A represents the clamp-bar, to the lower face of which the holding-clamps B B' are secured, one of said clamps B being cast with or otherwise rigidly connected to the bar A, and the other, B', being made adjustable on said bar, in such manner that it may be adjusted nearer to or further from the clamp B. In the drawing, the clamp B', which consists of an angle-iron, or a short horizontal bar having vertical lugs or ears at its ends, and provided with a set-screw, by means of which, and the opposing lug, the shoe is seized and held, is represented as provided with a set-screw or screws, or an adjustable shank of dove-tail form, fitting and working back and forth in a slot of corresponding form in the bar A, for the purpose of effecting the desired adjustment of said clamp relative to fixed clamp B. Other means for effecting this adjustment may be used if preferred. The purpose of the clamps is to secure the machine or implement firmly to the shoe upon the opposite arms or sides thereof, and by the adjustment described, the distance of the clamps from each other is varied to suit the varying sizes or widths of shoes to which it may be applied. The bar A, as represented, is made of dove-tail form, (narrowest at the bottom,) and has attached to it a slide, C, having a dove-tail groove or recess fitting bar A, and provided with a central pivot or swivel, D, upon the enlarged, squared head of which is mounted the adjustable carrying-arm E. Said arm E is made in form substantially as represented in fig. 1, and is slotted to receive the swivel-head D, and adapt it to be adjusted longitudinally thereon. F is a cap-piece or straddling standard, embracing the swinging arm, and resting at the opposite sides thereof upon the clamp-bar, and f is a set-screw, passing centrally through cap F, and into the swivel-head D, for the purpose of tightening the slide upon the clamp-bar, after it has been adjusted to the desired position thereon. G is a circular file, mounted in the fork at the outer swinging end of arm E upon a vertical or slightly inclined shaft, H, which has its bearings in the fork e e'. Said file is keyed or otherwise secured to shaft H in such manner as to turn with the shaft when the latter is rotated. The upper end of the shaft H is squared to receive the crank-arm I, by which it is operated. J is a removable cap-plate, secured to the swinging arm E, by means of a set-screw, or other equivalent device. The plate J is made in form represented in the sectional perspective view, fig. 4, being provided with a collar or sleeve which embraces the shaft, and fits in the socket or bearing in arm e', said socket or bearing being necessarily enlarged, to permit the insertion and withdrawal of the enlarged or squared portion of the shaft upon which the circular file is mounted. Said plate J serves to hold the shaft in place in its bearings in arms e e', and by its removal, and the withdrawal of the shaft endwise, the file is released, and may be readily removed and replaced when desired. K is a handle, secured to the swinging arm E at its heel-end, by means of which the said arm is controlled in its movements, and the desired pressure given to the file when in operation.

In operation, the clamp-bar, with its swinging arm and other appendages, is firmly clamped to the shoe in a manner that will be readily understood from the foregoing description. The operator then adjusts the swinging arm upon said bar, to bring it into the desired relation to the calk to be operated upon, when, seizing the handle K, the desired pressure of the file against the calk may be given, while, at the same time, by vibrating the handle, the file is made to traverse back and forth over the calk, and the required rotation being given thereto through the crank I, the calk is readily and rapidly filed away, until the desired degree of sharpness is secured. It will be seen that the shaft of the file, while in operation, is in a vertical, or nearly vertical position, or, in other words, in a line parallel, or nearly parallel with the calk, in the direction of its depth or length. It may be slightly varied from such parallel relation, to cause it to cut more rapidly at the point of the calk, or, if preferred, the file may be made in the form of a section of a cone, or with a bevelled face, to give it the desired angle. Other modifications may be made in the form of the parts, or in the means for effecting the several adjustments described, without departing from my invention.

Having now described the construction and operation of my invention, what I claim, and desire to secure by Letters Patent, is—

1. The clamp-bar A, or its equivalent, adapted to be secured to the shoe, substantially as and for the purpose set forth.
2. The adjustable swinging arm, provided with the rotary file G, in combination with the clamp-bar, or its equivalent, substantially as described.
3. The rotating circular file, arranged on a vertical, or nearly vertical shaft, and operating substantially as and for the purpose described.
4. The removable sleeved cap or plate J, for holding the shaft and circular file in place as described.
5. The standard F and set-screw f, in combination with the dove-tail slide C, for holding said slide in place on the clamp-bar as described.

JOHN JOHNSON.
